HOLDER FOR RAZOR BLADES

Filed March 18, 1925

FIG. 3

FIG. 5

FIG. 6

FIG. 7

FIG. 8

INVENTOR
Leonard Joy

UNITED STATES PATENT OFFICE.

LEONARD JOY, OF LAKE TOWNSHIP, MACOMB COUNTY, MICHIGAN.

HOLDER FOR RAZOR BLADES.

Application filed March 18, 1925. Serial No. 16,392.

My invention relates to improvements in the design and construction of a holder for razor blades (laminar type, or very thin compared with length and breadth) having two cutting or shaving edges opposite to each other, and provided with means (perforations), practiced in them for relative location in the razor (safety razor), as in the Gillette (trade-name) safety razor and the like.

With this my design and construction of a holder for Gillette (trade-name) safety razor blades, the aforesaid shaving blade can be located relatively to the holder in the same manner as located relatively to the Gillette (trade-name) safety razor, interlocked to the holder by mechanical means as will be shown and explained in this specification; and while so firmly held in said holder, the blade can be resharpened by means of strapping or honing its cutting edges, after being dulled through use in shaving; and in the very same way, or manual process, as used by an artisan 20 barber when he resharpenes his razors of the manual type, by long strokes of reciprocating character with the sides of the cutting edge of the blade, bearing upon a stretched and held taut leather strap used for this purpose, or by honing the sides of the cutting edge of the blade upon abrasive material stones (commonly called hones) and by the same manual process used by the aforesaid artisan barber in the performance of these manual processes of 30 sharpening his razors.

The usefulness of this my construction of a holder for laminar razor blades as set forth above is self evident as all users of such types of razor blades will benefit by improving the cutting or shaving qualities of their razors (safety razors), Gillette's (trade-name) safety razors specially, by adequate, easy and simple manual methods of either strapping or honing the blades they use, without the necessity of employing expert operators and complex or inefficient mechanical contrivances actually dispensed and made use of for the purposes as set forth heretofore.

The following is a detailed description of my laminar razor blade holder of the type and character as heretofore mentioned:

In the accompanying drawing Fig. 1, is a plan view of the holder with a Gillette's

(trade-name) safety razor blade outlined therein relatively located and shown;

Fig. 2 is an end view of Fig. 1.

Fig. 3 is an elevation or front view of the holder.

Fig. 4 is a plan view of the holder with outlines of safety razor blade in relative location, showing the open position of the holder, or position for the locating or positioning and vice-versa of the aforesaid razor blade preparatory to sharpening or removing the same, prior to or after it has been sharpened by the manual processes of strapping or honing as set forth.

Fig. 5 is a sectional view through line 16-16 in Fig. 4;

Fig. 6 is a sectional view through line 17-17 in Fig. 1;

Fig. 7 is a sectional view through line 18-18 in Fig. 4; and

Fig. 8 is a longitudinal or lengthwise sectional view through 19-19 in Fig. 1, and looked at in the direction of the arrows.

Identical numbers in all the various figures refer to identical details of construction.

In Fig. 1, 1 is the body or frame of the holder, 2 is the rotative member of the construction, rotating about pivot 3 fastened and riveted to frame 1; 4 are locating pins for relatively locating laminar blade, as shown by outlines 15, and fastened by riveting to frame 1; 5 are clearance slots or recesses to clear pins 4, practiced circularly, upon rotating member 2, about its center of rotation or pivot 3, and so causing no interference in its circular movement by the blade locating pins 4; 6 is a plunger with knurled end, for locking in the closed position rotating member 2, and retained in relative position to the frame 1 by key or pin 8 pressed in frame 1, and giving to plunger 6 free axial to-and-fro movements within limited axial length determined by cylindrical undercut 7 in plunger 6 and to which pin 8 comes tangent at right angle to the axial disposition of plunger 6 inserted in axial bore 9, practiced in frame 1 and rotating member 2, aligned to both when in closed or interlocked position.

10 and 11 are circularly milled angular recesses, milled or formed circularly about center of rotation or pivot 3, in frame 1 into which fit the similarly formed ends 12 and 13 of the rotating member 2 when in axial

coincidence and disposition as shown by Figs. 1, 2, 3 and 8.

14 is a recess or seat practiced upon frame 1 and wherein laminar blade 15 is inserted and caused to be flush with the same axial plane of both frame 1 and rotating member 2.

From the foregoing enumeration it can be explained:

- 10 When laminar blade 15 has been inserted in its recess 14 in frame 1, and relatively located therein by locating pins 4, while rotating member 2 is in open position as shown in Fig. 4, the rotating member 2 can be rotated about pivot pin 3, swung under or into recesses 10 and 11 in frame 1, and thereon held by formed ends 13 and 12 respectively of rotating member 2 until axial coincidence of both frame 1 and rotating member 2 permits the introduction of plunger 6 into aligned bore 9 of rotating member 2 and so cause an interlocking of frame 1, rotating member 2 and laminar blade 15; and that while in this state of inter-relation 25 of above mentioned parts or details of the laminar razor blade holder and laminar blade 15, as set forth; the manual process of strapping or honing of said laminar razor blade can be practiced or executed by the 30 user of the heretofore mentioned and described holder for laminar razor blades as those used in the Gillette (trade-name) safety razor or in fact, for similarly constructed devices for shaving or any other 35 similar cutting purposes.

Concurrent to the above and consequent to the explanations as therein set forth and stated, I do claim:

1. A holder for safety razor blades comprising a frame having a hollow cylindrical handle and a flat faced blade receiving portion provided at its extremities with arcuate slots having inclined upper walls, said blade receiving portion being formed 45 intermediate its ends with a shallow groove in its upper face, a pair of spaced studs ex-

tending through and above the groove to position a blade in the groove, a pivot secured substantially centrally of the blade receiving portion, a holding member rotatable on said pivot and having arcuate ends with inclined upper walls adapted to fit in said slots or swing therethrough to either side of the frame, said holding member being also provided with spaced arcuate grooves in its lower face of sufficient depth to clear the studs during the swinging movements of the member, and means for securing the holder member in alignment with the blade receiving portion.

2. A holder for safety razor blades comprising a frame having a hollow cylindrical handle and a flat faced blade receiving portion provided at its extremities with arcuate slots having inclined upper walls, said blade receiving portion being formed intermediate its ends with a shallow groove in its upper face, a pair of spaced studs extending through and above the groove to position a blade in the groove, a pivot secured substantially centrally of the blade receiving portion, a holding member rotatable on said pivot and having arcuate ends with inclined upper walls adapted to fit in said slots or swing therethrough to either side of the frame, said holding member being also provided with spaced arcuate grooves in its lower face of sufficient depth to clear the studs during the swinging movements of the member and at its rear extremity with a semi-cylindrical bore, the blade receiving portion being also provided with a semi-cylindrical bore at its rear extremity adapted to align with the bores in the holding member and in the hollow handle, and a locking pin mounted within the hollow handle and adapted to be moved into locking position within the aligned bores in the blade receiving portion and the holding member.

LEONARD JOY.
